The ornamental design for a swivel mount, as shown and described.

DESCRIPTION

FIG. 1 is a rear perspective view taken from the top right corner of a swivel mount;
FIG. 2 is a rear perspective view taken from the bottom left corner of the swivel mount of FIG. 1;
FIG. 3 is a front elevation view of the swivel mount of FIG. 1;
FIG. 4 is an elevation view as viewed from the right side of the swivel mount of FIG. 1;
FIG. 5 is an elevation view as viewed from the left side of the swivel mount of FIG. 1;
FIG. 6 is a top plan view of the swivel mount of FIG. 1;
FIG. 7 is a bottom plan view of the swivel mount of FIG. 1;
FIG. 8 is a front perspective view taken from the top right corner of the swivel mount of FIG. 1, wherein a mounting portion of the swivel mount is shown in a pivoted configuration;
FIG. 9 is a rear perspective view taken from the top right corner of the pivoted swivel mount of FIG. 8;
FIG. 10 is a rear perspective view taken from the bottom left corner of the pivoted swivel mount of FIG. 8;
FIG. 11 is a front elevation view of the pivoted swivel mount of FIG. 8;
FIG. 12 is a rear elevation view of the pivoted swivel mount of FIG. 8;
FIG. 13 is an elevation view as viewed from the right side of the pivoted swivel mount of FIG. 8;

FIG. 14 is an elevation view as viewed from the left side of the pivoted swivel mount of FIG. 8;
FIG. 15 is a top plan view of the pivoted swivel mount of FIG. 8;
FIG. 16 is a bottom plan view of the pivoted swivel mount of FIG. 8;
FIG. 17 is a front perspective view taken from the top right corner of the swivel mount of FIGS. 1 and 8, wherein both the mounting portion of the swivel mount and a base portion of the swivel mount are shown in pivoted configurations;
FIG. 18 is a front elevation view of the pivoted swivel mount of FIG. 17;
FIG. 19 is a rear elevation view of the pivoted swivel mount of FIG. 17;
FIG. 20 is an elevation view as viewed from the right side of the pivoted swivel mount of FIG. 17;
FIG. 21 is an elevation view as viewed from the left side of the pivoted swivel mount of FIG. 17;
FIG. 22 is a top plan view of the pivoted swivel mount of FIG. 17; and,
FIG. 23 is a bottom plan view of the pivoted swivel mount of FIG. 17.

The dot-dash-type broken lines shown in the drawing views define the boundaries of the claimed design and form not part of the claimed design. The dash-dash-type broken lines shown in the drawing views are for the purpose of illustrating portions of the swivel mount that form no part of the claimed design.
